(57) **CLAIM**

The ornamental design for a diffusing evaporator of active substances, as shown and described.

DESCRIPTION

FIG. 1 is a front, top and side perspective view illustration of a diffusing evaporator of active substances, according to the new design;

FIG. 2 is a front view illustration thereof;

FIG. 3 is a side view illustration thereof;

FIG. 4 is a bottom view illustration thereof;

FIG. 5 is another side view illustration thereof; and,

FIG. 6 is a top view illustration thereof.

The rear view is a mirror image of the front view.
